CLAIM

The ornamental design for a display shelf, as shown and described.

DESCRIPTION

FIG. 1 is a top, front, and right side perspective view of a display shelf showing my new design, the broken-line depiction of a portion of a shelving support being for illustrative purposes only and forming no part of the claimed design;

FIG. 2 is a front elevational view thereof;

FIG. 3 is a right side elevational view thereof, the left side being a mirror image of that shown;

FIG. 4 is a rear elevational view thereof;

FIG. 5 is a top plan view thereof; and

FIG. 6 is a bottom plan view thereof.

FIG. 2

FIG. 3

FIG. 4

FIG. 5

FIG. 6
